(57) **CLAIM**

The ornamental design for a rack, as shown and described.

DESCRIPTION

FIG. 1 is an isometric view of a rack showing my new design.

FIG. 2 is a front view thereof.

FIG. 3 is a top view thereof.

FIG. 4 is a left side view thereof.

FIG. 5 is a right side view thereof.

FIG. 6 is a back view thereof; and,

FIG. 7 is a bottom view thereof.

The broken-line disclosure in the views is understood to be for illustrative purposes only and forms no part of the claimed design.
